An electromechanical driving circuit for use in electronic clocks and watches adapted to supply electromagnetic pulses produced in two coils S_1 and S_2 arranged between permanent magnets secured to an oscillatory moving body such as a balancing wheel of an electronic clock or watch. Provision is made of a single condenser C adapted to be supplied with an electric current relating to induced voltages produced in the coils S_1 and S_2 when transistors whose collectors are connected to the coils S_1 and S_2 , respectively, are made alternately conductive.

DRIVING CIRCUITS FOR ELECTRONIC CLOCKS
AND WATCHES

This invention relates to electromechanical driving circuits for use in electronic clocks and watches which continuously drive an oscillatory moving body by means of a small current supply source such as an electric battery etc. and, more particularly, to an electromechanical driving circuit which can reliably supply electromagnetic pulses to an electromechanical driven system of electronic clocks and watches.

A principal object of the invention is to provide an electromechanical driving circuit which can improve the driving efficiency of a conventional electromechanical circuit which makes use of a small current supply source, which can incorporate circuit component parts of integrated circuit, which can be manufactured in a simple and easy manner and is small in size, and which can improve the space factor in an electronic clock and watch.

A conventional electromechanical driving circuit heretofore used and adapted to drive, for example, an oscillatory magnet type balancing wheel of an electronic wrist watch will be described with reference to FIGS. 1a and 1b. In FIGS. 1a and 1b, C designates an electromechanical driving circuit and E an electric current supply source. Reference numeral 1 designates a plurality of permanent magnets, 2 shows a balancing wheel a part or all of which is made of a ferromagnetic material and 3 designates a shaft of the balancing wheel 2. The balancing wheel 2 is secured to the shaft 3 and adapted to be oscillatorily moved together with the shaft 3. Numeral 4 is a hair spring adapted to oscillatorily move the balancing wheel 2, and 5 shows a substrate and 6 a supporting frame secured to the substrate 5. The upper and lower ends of the shaft 3 are journaled in the substrate 5 and the frame 6, respectively. S₁ and S₂ designate coils arranged between the permanent magnets 1 which are arranged in diametric opposition and are of opposite polarities. An induced voltage e_{s1} produced in the coil S₁ is opposite in polarity to an induced voltage e_{s2} produced in the coil S₂ at the same instant as shown in FIG. 2.

In FIG. 3 is shown one example of the conventional electromechanical driving circuit C in which one of the terminals of the coils S₁ is connected through a condenser Ca to the base of a transistor Tr, while one of the terminals of the coil S₂ is connected to the collector of the transistor Tr. Between the other terminal of the coil S₂ and the emitter of the transistor Tr is connected an electric current supply source E. The transistor Tr serves as a switch for opening and closing a circuit including the coil S₂ by the induced voltage produced in the coil S₁ and applied through the condenser Ca to the base of the transistor Tr. The opening and closing time of the switching transistor Tr is controlled by the electric charge accumulated in the condenser Ca and by a time constant determined by the condenser Ca and a resistor R connected in parallel thereto. As a result, an intermittent current flows through the coil S₂. As seen from the above, in this circuit the operation of the coil S₁ is different from that of the coil S₂. That is, the coil S₁, which operates as a control coil can not be used in place of the coil S₂ which operates as a driving coil unless the connection of the circuit is changed. Thus, a driving force which can continue the oscillatory move-

ment of the balancing wheel 2 is produced by the coil S₂ only once a period.

In FIG. 4 is shown another example of the conventional electromechanical driving circuit C in which one of the terminals of a coil S₁ and one of the terminals of a coil S₂ are connected through junction points A and B to the collectors of transistors Tr₁ and Tr₂, respectively, while the other terminals of the coils S₁ and S₂ are connected through an electric current supply source E to the emitters of the transistors Tr₁ and Tr₂. The junction point A is connected through a condenser Ca₁ to the base of the transistor Tr₂, while the junction point B is connected through a condenser Ca₂ to the base of the transistor Tr₁. This circuit arrangement is a multivibrator in which self-relaxation oscillation is capable of passing a current through each of the coils S₁ and S₂ even when the oscillatory motion of the balancing wheel 2 is stopped, that is, even when the induced voltage is not produced in each of the coils S₁ and S₂, thereby self-sustaining the oscillatory movement of the balancing wheel 2. A positive induced voltage e_{s1} produced in the coil S₁ makes the transistor Tr₂ conductive, while a positive induced voltage e_{s2} produced in the coil S₂ makes the transistor Tr₁ conductive. That is, if the coil S₁ becomes operative as the control coil, the coil S₂ is operated as the driving coil and conversely if the coil S₂ becomes operative as the control coil, the coil S₁ is operated as the driving coil, and as a result, the circuit shown in FIG. 4 is capable of producing driving forces twice during each period which can continue the oscillatory movement of the balancing wheel 2. If a current i flows through the coil S₁ or S₂ and an induced voltage e is produced therein, the effective power of the electromechanical driving circuit C shown in FIG. 4 is given by ei. The induced voltage e_{s1} or e_{s2} produced in the coil S₁ or S₂ changes as a function of time t as shown in FIG. 2. It is most preferable to make a current flow through the coil S₁ or S₂ at that instant which is near the instant at which the largest induced voltage e_{s1} or e_{s2} is produced. If the driving force produced by the circuit shown in FIG. 3 is assumed to be equal to the driving force produced by the circuit shown in FIG. 4, a current must flow through the circuit shown in FIG. 3 from that instant which is closest to the instant at which the largest induced voltage is produced since the driving force is produced once a period. The circuit shown in FIG. 4, however, is capable of making the current flow at the instant when the induced voltage e is high. As a result, the driving efficiency of the circuit shown in FIG. 4 is higher than that of the circuit shown in FIG. 3. But, the circuit shown in FIG. 4 has the disadvantage that the component parts constituting the circuit are large in number. This is a vital defect in a wrist watch whose space, in which all of these component parts are contained, is limited. Particularly, an electromechanical driving circuit adapted to operate the balancing wheel etc. in a low frequency has to utilize a condenser Ca which is large in capacity and size. The use of such a condenser Ca results in a difficulty in the manufacture of the electromechanical driving circuit.

A primary object of the invention, therefore, is to provide an electromechanical driving circuit for use in clocks and watches, which can incorporate all of component parts into a semiconductor integrated circuit so as to reduce the condenser Ca in capacitance and in size without neglecting any advantage of the conven-

tional electromagnetic driving circuit as shown in FIG. 4.

In general, the dimensions of the circuit elements such as transistor, resistor, diode etc. which can easily be incorporated into the integrated circuit can be made small by comparison with the dimensions of the condenser C_a . It might be considered that the circuit consisting, for example, of transistor, resistor, diode etc. would be of complex in construction. But, such disadvantages of the complex circuit is minor when compared with the advantage obtained by the reduction in size and capacitance of the condenser C_a .

As will hereinafter be described, the electromechanical described, the electromechanical driving circuit according to the invention takes into consideration the construction of the semiconductor integrated circuit so that the resistor designated by R and the transistor designated by Tr for ease of illustrating the operation of circuit represent any other circuit elements.

The invention makes use of the basic circuit operation that can produce the driving force twice a period owing to the above mentioned reasons. But the arrangement and operation of the circuit per se according to the invention are entirely different from those of the conventional circuit shown in FIG. 4.

The invention will now be described with reference to the accompanying drawings, in which:

FIG. 1a is a sectional view illustrating a relation between a balancing wheel of an electronic watch and a circuit for driving the balancing wheel;

FIG. 1b is plan view of the part shown in FIG. 1;

FIG. 2 diagrammatically illustrates a relation between the operation of the balancing wheel shown in FIGS. 1a and 1b and induced voltages produced in the coils S_1 and S_2 ;

FIGS. 3 and 4 are conventional driving circuit diagrams; and

FIGS. 5, 6 and 7 are driving circuit diagrams each embodying the invention.

In FIG. 5 is shown a first embodiment of the electromechanical driving circuit according to the invention whose arrangement of component parts and operation thereof will now be described. In the present embodiment, one of the terminals of a coil S_1 is connected through a junction point A to the collector of a transistor Tr_1 , while one of the terminals of a coil S_2 is connected through a junction point B to the collector of a transistor Tr_2 . The other terminals of the S_1 and S_2 are connected through an electric current supply source E to the emitters of the transistors Tr_1 and Tr_2 . An induced voltage produced at the junction point A is opposite in polarity to that produced at the junction point B as described above. The junction points A and B are connected to the emitters of transistors Tr_3 and Tr_4 , respectively, whose bases are connected through a common resistor R_3 to the electric current supply source E. The collectors of the transistors Tr_3 and Tr_4 are connected in common to a junction point C. Between a junction point D and the junction point C are connected in parallel a condenser C_a and a resistor R_4 . The bases of the transistors Tr_5 and Tr_6 are connected through the junction points A and B to the coils S_1 and S_2 , respectively, while the emitter of the transistor Tr_5 is connected to the base of the transistor Tr_2 and the emitter of the transistor Tr_6 is connected to the base of the transistor Tr_1 .

The circuit shown in FIG. 5 can operate as follows. When the electric potential at the junction point A caused by the induced voltage e_{s1} produced in the coil S_1 causes the transistor Tr_5 to shift from its nonconductive region to its active or conductive region, the electric potential at the junction point B caused by the induced voltage e_{s2} produced in the coil S_2 causes the transistor Tr_6 to shift further to its nonconductive region. As a result, the electric potential at the junction point A only is transmitted to the junction point C. The electric potential at the junction point A also causes the transistor Tr_5 to shift toward its active region and is transmitted through the transistor Tr_5 to the base of the transistor Tr_2 so as to make it conductive, and as a result, a current supplied from the electric current supply source E flows through the coil S_2 . If the potential at the junction point B causes the transistor Tr_4 to shift toward its active region, a current supplied from the electric current supply source E flows through the coil S_1 . Thus, the circuit shown in FIG. 5 receives a signal from the coil S_1 so as to make a current flowing through the coil S_2 and receives a signal from the coil S_2 so as to make a current flowing through the coil S_1 , these operations being effected alternately. As a result, the circuit shown in FIG. 5 operates to produce a driving force twice a period. Both the signal delivered from the coil S_1 and the signal delivered from the coil S_2 are transmitted through the junction points C-D and the transistors Tr_5 and Tr_6 to the transistors Tr_2 and Tr_1 , respectively, to charge the condenser C_a . Thus, the electric charge charged in the condenser C_a and the change of the electric potential across the junction points C-D relative to a time constant determined by the condenser C_a and the resistor R_4 become a threshold voltage of the transistors Tr_1 and Tr_2 which can control the time at which the driving force is produced and can control the amplitude of the signals delivered from the coils S_1 and S_2 , respectively.

Representative numerical values of the component parts of the embodiment shown in FIG. 5 are as follows.

S_1 and S_2 : 12 microns in diameter, 1500 turns, $3\text{ K}\Omega$ in resistivity

R_3 : $1\text{ M}\Omega$ in resistivity

R_4 : $10\text{ M}\Omega$ in resistivity

C_a $0.1\text{ }\mu\text{F}$ in capacitance.

In FIG. 6 is shown a second embodiment of the electromechanical driving circuit according to the invention whose arrangement of component parts and operation thereof will now be described. In the present embodiment, one of the terminals of a coil S_1 is connected through a junction point A to the collector of a transistor Tr_1 , while one of the terminals of a coil S_2 is connected through a junction point B to the collector of a transistor Tr_2 . The other terminals of the coils S_1 and S_2 are connected through an electric current supply source E to the emitters of the transistors Tr_1 and Tr_2 . An induced voltage produced at the junction point A is opposite in polarity to that produced at the junction point B as described above. The junction points A and B are connected to the emitters of transistors Tr_7 and Tr_8 , respectively, whose bases are connected in common to a junction point C which is connected through a condenser C_a , which electrically represents one condenser, to one of the terminals of an electric current supply source E. In parallel with the condenser C_a is connected a resistor R_5 so as to determine a time constant. The collector of the transistor Tr_7 is connected

through a resistor R_7 to the base of the transistor Tr_2 , while the collector of the transistor is connected through a resistor R_6 to the base of the transistor Tr_1 . The resistance values of these resistors are made larger than zero. This is determined by design based on the characteristic of the transistor Tr_7 , Tr_8 etc.

The operation of the circuit shown in FIG. 6 is as follows. If the electric potential at the junction point A delivered from the coil S_1 causes the transistor Tr_7 to shift from its nonconductive region to its active region, the induced voltage in the coil S_2 causes the transistor Tr_8 to shift its nonconductive region further toward its more intensively nonconductive region. As a result, only the electric potential at the junction point A results in a flow of current from the condenser Ca to the electric current supply source E. In addition, the transistor Tr_2 becomes conductive so that a current flows from the electric current supply source E to the coil S_2 . If the electric potential at the junction point B causes the transistor Tr_8 to shift to its active region, a current is supplied from the electric current supply source E to the coil S_1 . Thus, the circuit shown in FIG. 6 is operated such that arrival of the signal from the coil S_1 causes a current flow through the coil S_2 and that arrival of the signal from the coil S_2 causes a current flow through the coil S_1 , and as a result, the circuit as a whole is operated so as to produce the driving force twice a period. Since both the signal delivered from the coil S_1 and the signal delivered from the coil S_2 flow from the condenser Ca to the electric current supply source E, the electric charge accumulated in the condenser Ca and the charge in time of the electric potential produced at the junction point C and determined by the time constant of the condenser Ca and the resistor R_1 become a threshold voltage of the transistors Tr_7 and Tr_8 and hence become a threshold voltage of the transistors Tr_1 and Tr_2 . The threshold voltage is capable of controlling the timing and the amplitude of the current for producing the driving force and flowing through the coils S_1 and S_2 .

Representative numerical values of the component parts of the embodiment shown in FIG. 6 are as follows.

R_5	10 M Ω
R_6	500 K Ω
R_7	500 K Ω
Ca	0.1 μ F

In FIG. 7 is shown a third embodiment of the electromagnetic driving circuit according to the invention whose arrangement of component parts and operation thereof will now be described. In the present embodiment, one of the terminals of a coil S_1 is connected through a junction point A to the collector of a transistor Tr_1 , while one of the terminals of a coil S_2 is connected through a junction point B to the collector of a transistor Tr_2 . The other terminals of the coils S_1 and S_2 are connected through an electric current supply source E to the emitters of the transistors Tr_1 and Tr_2 , respectively. An induced voltage produced at the junction point A is opposite in polarity to that produced at the junction point B as described above. The junction points A and B are connected to the emitters of transistors Tr_9 and Tr_{11} , respectively, whose bases are connected through the collector-emitter paths of transis-

tors Tr_{10} and Tr_{12} in common to a junction point C which is connected through a condenser Ca , which electrically represents one condenser, to one of the terminals of the electric current supply source E. In parallel with the condenser Ca is connected a resistor R_8 to determine a time constant. The collector of the transistor Tr_9 is connected through a resistor R_{10} to the base of the transistor Tr_2 , while the collector of the transistor Tr_{11} is connected through a resistor R_9 to the base of the transistor Tr_1 . The resistance values of these resistors are made larger than zero. This is determined by design based on the characteristic of the transistors Tr_9 , Tr_{11} etc.

Provision is made of a discharging circuit for the electric potential at the junction point C and consisting of transistors Tr_{13} and Tr_{14} . The junction point C is connected through a resistor R_{11} to the base of the transistor Tr_{13} whose emitter-collector path is connected through the base-emitter path of the transistor Tr_{14} across the electric current supply source E. The collector of the transistor Tr_{13} is connected to the base of the transistor Tr_{14} whose collector is connected to a junction point between the resistor R_{11} and the base of the transistor Tr_{13} while the emitter of the transistor Tr_{14} is connected to the emitters of the transistors Tr_1 and Tr_2 .

The operation of the circuit shown in FIG. 7 is as follows. If the electric potential at the junction point A becomes high owing to the induced voltage produced at the coil S_1 , the electric potential at the junction point B becomes low. In this state the transistor Tr_{10} is shifted from its nonconductive region to its active region, and as a result, the transistor Tr_9 is shifted to its active region. Thus, the condenser Ca is charged by a current flowing through the base-emitter of the transistor Tr_{10} and by a current flowing through the emitter-base of the transistor Tr_9 and the collector-emitter of the transistor Tr_{10} .

If the transistor Tr_9 becomes conductive, a current flows through its emitter-collector path and the resistor R_{10} to the base of the transistor Tr_2 , and as a result, the transistor Tr_2 becomes conductive and hence a current is supplied from the electric current supply source E to the coil S_2 .

If the electric potential at the junction point B becomes high and the electric potential at the junction point A becomes low owing to the induced voltages produced in the coils S_1 and S_2 , the transistors Tr_{11} and Tr_{12} are shifted to their active regions and become conductive, respectively. Thus the condenser Ca is charged by a current flowing through the base-emitter path of the transistor Tr_{12} and by a current flowing through the emitter-base path of the transistor Tr_{11} and the collector-emitter path of the transistor Tr_{12} .

If the transistor Tr_{11} becomes conductive, a current flows through its emitter-collector path and the resistor R_9 to the base of the transistor Tr_1 , and as a result, the transistor Tr_1 becomes conductive and hence a current is supplied from the current supply source E to the coil S_1 .

Thus, also in the present embodiment, the signal delivered from the coil S_1 causes a current flow through the coil S_2 , while the signal delivered from the coil S_2 causes a current flow through the coil S_1 , and as a result, the circuit as a whole operates to produce a driving force for oscillatorily moving the balancing wheel twice a period.

In addition, the condenser Ca is charged twice a period. The electrical potential at the junction point C becomes high when the condenser Ca is charged and is decreased when the charging of the condenser Ca becomes ceased. The decrease of the electrical potential at the junction point C is changed in function with time in dependence with the time constant determined by the condenser Ca and the resistor R₈. The function and effect of the condenser Ca are the same as those of the condenser Ca described with the embodiments shown in FIGS. 5 and 6.

In the present embodiment, the discharging circuit consisting of transistors Tr₁₃ and Tr₁₄ is connected across the condenser Ca for the purpose of improving the property of starting the oscillatory operation of the circuit.

In general, the lower the electric potential at the junction point C the more easily the transistor Tr₁₀ or Tr₁₂ becomes conductive and hence the property of starting the oscillatory operation of the circuit can be improved. But, the higher the electric potential at the junction point C the lesser the dark current flows and hence the driving efficiency of the circuit can be improved.

As stated hereinbefore, the electric potential at the junction point C is discharged in function exponentially with the time constant determined by the condenser Ca and the resistor R₈. If this time constant is large, it takes a long time to discharge the electric potential at the junction point C. Under such condition, if the amplitude of the oscillatory operation of the circuit becomes suddenly decreased owing to exterior disturbances etc., it takes a long time to restore the amplitude thus decreased to its normal amplitude, thereby degrading the property of starting the oscillatory operation of the circuit.

In the embodiment shown in FIG. 7, provision is made of the discharging circuit consisting of the transistors Tr₁₃ and Tr₁₄ connected across the condenser Ca and which can operate when the electric potential at the junction point C becomes lower than a given level to expedite the rate of discharging the condenser Ca.

The discharging circuit shown in FIG. 7 will operate as follows.

If the electric potential at the junction point C is discharged by the time constant determined by the condenser Ca and the resistor R₈ and reaches to a given potential, the transistor Tr₁₃ becomes conductive. Thus, the transistor Tr₁₄ becomes conductive, and as a result, the condenser Ca is discharged through the collector-emitter path of the transistor Tr₁₄. Thus, it is possible to shorten the discharging time of the condenser Ca if compared with the discharging time determined by the time constant of the condenser Ca and the resistor R₈, thereby considerably improving the property of starting the oscillatory operation of the circuit.

The resistor R₁₁ connected between the junction point C and the discharging circuit can further improve the property of starting the oscillatory operation of the circuit.

Representative numerical values of the component parts of the embodiment shown in FIG. 7 are as follows.

-Continued

Ca	0.1 μ F
R ₉	500 K Ω
R ₁₀	500 K Ω
R ₁₁	500 K Ω

The conductivity type of the transistor Tr may be changed from NPN type to PNP type or from PNP type to NPN type without affecting the operation of the circuit. In this case, however, care must be taken to charge the polarity of the electric current supply source E correspondingly.

The electromechanical driving circuit according to the invention has advantages that use may be made of only one condenser Ca for the purpose of controlling the amplitude of the current for producing the driving force and flowing through the coils S₁ and S₂, that the efficiency for driving the balancing wheel can be improved; and that the transistor Tr and the resistor R may be incorporated into an integrated circuit to provide a driving circuit or a balancing wheel of a wrist watch, which is extremely small in size and reliable in operation.

As stated hereinbefore, the embodiments shown in FIGS. 5, 6 and 7 can produce the driving force twice a period. In this case, an induced current flows through the condenser Ca twice a period. As a result, the condenser Ca operates for a period which is equivalent to half the operating period of the condenser Ca used in the conventional circuits shown in FIGS. 3 and 4, and as a result, the capacity of the condenser Ca in the circuits shown in FIGS. 5, 6 and 7 may be made smaller than half the capacity of the condenser Ca in the circuits shown in FIGS. 3 and 4. This feature of the invention renders it possible to make the wristwatch thin in thickness and small in size. In addition, the circuits shown in FIGS. 5, 6 and 7 have a self-starting property to be described later.

In the circuits shown in FIGS. 5, 6 and 7, the signal is transmitted in a direct current connection, while the operation is effected in an alternating current connection. Thus, the circuits shown in FIGS. 5, 6 and 7 operate as a multivibrator. For example, in the circuit shown in FIG. 6, the transistor Tr₃ or Tr₄ becomes conductive owing to the presence of component parts which are slightly different in design values and owing to electrical shocks occurring at the time of switching in the electric current supply source E, thereby producing the driving force. The driving force is once produced, the circuit shown in FIG. 6 will continuously operate as described above.

The invention has been described in case of applying it to an electromechanical driving circuit for use in electronic clocks and watches whose balancing wheel is provided with magnets associated with separate coils, respectively. The invention is not limited to such circuit and may be applied to any type of electromechanical driving circuit.

What is claimed is:

1. An electromechanical driving circuit for use in electronic clocks and watches comprising an oscillatory moving body, a plurality of permanent magnets secured to said oscillatory moving body at its diametrically opposite parts, two coils S₁ and S₂ each arranged between said permanent magnets and adapted to be moved relative to said permanent magnets, which comprises first transistors with emitters earthed and collec-

tors connected to said coils S_1 and S_2 , respectively, and a condenser Ca operatively connected through second transistors to junction points between the collectors of said first transistors and said coils S_1 and S_2 , respectively, and adapted to be supplied with an electric current relating to induced voltages produced in said coils S_1 and S_2 , whereby said first transistors are made alternately conductive in response to said electric current.

2. An electromechanical driving circuit for use in electronic clocks and watches claimed in claim 1 which further comprises a resistor connected in parallel with said condenser Ca .

3. An electromechanical driving circuit for use in electronic clocks and watches as claimed in claim 1 wherein said condenser Ca is connected to a junction point between the same electrodes respectively of said second transistors.

4. An electromechanical driving circuit for use in electronic clocks and watches comprising

an oscillatory moving body,

permanent magnets secured to said oscillatory moving body at its diametrically opposite position relative to each other,

two coils each arranged between said permanent magnets and adapted to be moved relative to said permanent magnets,

an electric current supply source,

first transistors having grounded emitters and having collectors connected through first junction points to said coils, respectively,

resistors,

second transistors having collectors connected through said resistors, respectively to the bases of said first transistors, respectively, and having emitters connected to said first junction points, respectively, and having bases operatively connected to a common junction point, and

a parallel circuit including a condenser and another

resistor,
one end of said parallel circuit being connected to said common junction point.

5. An electromechanical driving circuit for use in electronic clocks and watches claimed in claim 4 which further comprises a discharging circuit connected across said condenser Ca and adapted to be operated when the discharging voltage of said condenser Ca is decreased to a level lower than a given level.

10 6. The electromechanical driving circuit, as set forth in claim 7, further comprising
third transistors having bases, respectively, connected to said first junction points,
the bases of said second transistors are connected through base-emitter paths respectively, of said third transistors, respectively, to said common junction point,
said parallel circuit is connected between said common junction point and the emitters of said first transistors.

20 7. The electromechanical driving circuit, as set forth in claim 4, wherein
said second transistors with bases are connected in common through said common junction point, and the other end of said parallel circuit is connected to the ground.

8. The electromechanical driving circuit, as set forth in claim 6, which further comprises
a discharging circuit including,
a nother transistor having a collector-emitter path connected across said condenser, and
a further transistor having a base connected to the collector of said other transistor, and having a collector connected to the base of said other transistor and having an emitter connected to another junction point between said two coils and said electric current supply source.
